DESIGN FOR A BLOUSE

Irving Geist, New York, N. Y.

Application August 6, 1936, Serial No. 64,266

Term of patent 3½ years

To all whom it may concern:

Be it known that I, Irving Geist, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The interwoven lines on the neckband portion of the blouse represent braiding.

I claim:

The ornamental design for a blouse, substantially as shown, and described.

IRVING GEIST.
